UNITED STATES PATENT OFFICE.

ARTHUR MUTSCHELLER, OF NEW YORK, N. Y., ASSIGNOR TO WAPPLER ELECTRIC CO., INC., A CORPORATION OF NEW YORK.

STEREOSCOPE.

Application filed October 10, 1919. Serial No. 329,797.

To all whom it may concern:

Be it known that I, ARTHUR MUTSCHELLER, a citizen of the United States, residing at New York, county of New York, and 5 State of New York, have invented certain new and useful Improvements in Stereoscopes, of which the following is a full, clear, and concise description.

My invention relates to stereoscopes, and 10 more particularly to stereoscopes of the kind using plates of large size, spaced widely apart.

More particularly stated, my invention comprehends a stereoscope of the type just 15 mentioned and in which I so mount the stereoscope head, carrying a pair of mirrors or the equivalent thereof, as to render the head adjustable in a number of directions relatively to the plates, in order that the 20 images carried by the plates may be brought into exact optical coincidence.

Reference is made to the accompanying drawing forming a part of this specification, and in which like reference characters indicate like parts throughout the several figures.

Fig. 1 is a front elevation of one form of the stereoscope complete.

Fig. 2 is a fragmentary vertical section 30 through the stereoscope head and parts immediately associated therewith, and shows one form of flexible standard for permitting adjustments of the stereoscope head.

Fig. 3 is a fragmentary section somewhat 35 similar to Fig. 2, but showing a different form of flexible standard than that appearing in Fig. 2, for permitting the adjustments.

Fig. 4 is a fragmentary rear elevation of 40 the parts shown in Fig. 3.

Fig. 5 is a fragmentary plan showing the mountings for the standard used for supporting the stereoscope head, the standard appearing in section.

Fig. 6 is a section on the line 6—6 of 45 Fig. 1.

Fig. 7 is a fragmentary view, partly in front elevation and partly broken away, of another form of my device in which the 50 stereoscope head is made in halves adjustable relatively to each other.

Fig. 8 is a section on the vertical central

line of Fig. 7, looking in the direction indicated by the arrows at 8—8.

Fig. 9 is a section on the same line of Fig- 55 ure 7, looking in the direction indicated by the arrows at 9—9.

Table legs are shown at 6, 7, and may if desired be adjustable as to length. Braces 8, 9, are connected with the table legs, and 60 extend therefrom to a pair of rails 10, 11. These rails are made preferably of angle iron and are connected together by end pieces 12, 13. The rails are provided with flange portions 14, 15, as shown more particularly 65 in Fig. 5, these flange portions together serving as a track or way. Cross pieces 16 extend from one of the rails to the other and serve to brace the rails.

The parts thus far described constitute 70 table of the stereoscope.

A pair of carriages are shown at 17 and 18, and in this instance have each the form of a flat block. Each carriage is provided with wheels 19 which support it and which 75 rest upon the track or way consisting of two flange portions 14, 15, of the rails.

Resting upon the carriages 17, 18, are the illuminating boxes 20, 21. These are provided with window frames 22, 23, and backings 24, 25, the window frames and backings together serving as plate supports. Each illuminating box is adjustable relatively to the carriage upon which it is mounted, so that the plate carried by the 85 box can be brought into position suitable for enabling it to be viewed to the best advantage.

Extending across the table are two guide bars 26, 27, which are supported by brackets 90 28, 29, these brackets being secured upon the rail. Slidably mounted upon these supporting bars are two bearings 30, 31, each of cylindrical form, as shown more particularly in Fig. 5. Connected rigidly with the 95 two bearings 30, 31, is a pedestal 32. Each bearing 30, 31, is preferably integral with the pedestal. The bearings are provided with handles 33, 34.

The pedestal 32 is provided with an up- 100 wardly extending portion 35, having in this instance the form of a rather flat neck. A standard 36 having the form of a flat bar and provided with a slot 37, extends verti-

cally through the pedestal 32 with its neck 35. A bolt 38 extends through a hole in the wall of the neck 35 and is provided with a head 38^a of the form shown more particularly in Fig. 6. The head 38^a and the standard 36 are so shaped relatively to each other that the bolt is unable to turn relatively to the standard. Fitted upon the bolt is a wing nut 39. The operator by turning this wing nut may tighten it relatively to the neck 35, and by turning it in the opposite direction may loosen it. By first loosening the wing nut the operator may adjust the standard 36 vertically in relation to the pedestal 32, and the adjustment being completed he can tighten the wing nut and thus leave the parts affected firmly fixed in position as thus adjusted. The standard 36 at its top end is provided with a hole 40 of substantially cylindrical form as indicated in Fig. 2. A set-screw 41 extends through the adjacent wall of the standard, and into the hole 40. A plate 42 is provided with a reduced portion 42^a of substantially cylindrical form, adapted to fit neatly into the hole 40. The portion 42^a is provided with an annular groove 42^b, into which the point of the set-screw 41 may extend, as indicated in Fig. 2. The stereoscope head appears at 43, and is carried by the plate 42. The stereoscope head 43 is provided with a center post 44 and with a back 45. A set-screw 46, having a reduced threaded portion 47, is carried by the center post 44 and extends through a hole 48 in the back 45. The plate 42 extends through a hole 49 in the bottom of the stereoscope head 43. The stereoscope mirrors are shown at 50, 51, and are carried by the stereoscope head. Between these mirrors is a center piece 52 of substantially semi-cylindrical form. The stereoscope head is provided with blinders 53, 54 of the usual or any desired form.

Located between the plate 42 and the center part 44 is a friction plate 42^e, made of sheet celluloid. The set screw 46 is in practice turned just enough to clamp the friction plate firmly but not tightly so that the operator without touching the set screw 46 can grasp the stereoscope head and turn it in either a clockwise or a contra-clockwise direction, reckoning from the position of the operator as he stands normally facing the stereoscope.

55 The operator by loosening the set screw 41 can turn the stereoscope head upon an axis extending vertically or substantially vertically, that is, the operator can turn the stereoscope head upon the axis of the cylindrical portion 42^a of the plate 42. This done, he tightens the set screw 41 and by so doing he secures the stereoscope head firmly in a new position. In practice, however, it is seldom or never necessary to disturb the 60 set screw 41, because with a little care in ad-

justing the tightness of this screw the joint readily operates as a friction joint, so that the operator can merely grasp the stereoscope head and turn it by using very little exertion.

70 Between the two adjustments, one associated with the set screw 46 and the other with the set screw 41, the operator can give the stereoscope head 43 practically any adjustment desired in any direction. Thus the 75 mechanism for affecting the adjustments thus contemplated is the equivalent of a universal joint.

In the Figs. 3 and 4, I show mechanism differing slightly from that appearing in 80 Fig. 2, for the purpose of accomplishing the adjustments. The center post 44 is mounted upon a plate 55 to which it is secured by a set screw 46 having a reduced threaded portion 47. The plate 55 fits 85 against a friction plate 42^e, of the kind above described, and is provided with a hemispherical bearing 56 carrying a retaining ring 57 secured upon it by screws 58. The bearing with its retaining ring constitutes 90 a socket which fits upon a ball 59. This ball is carried by a stem 60 which is secured upon the top of a standard 61 provided with a slot 62 and having a general purpose similar to that of the standard 36 above described.

95 The ball and socket joint enables the stereoscopic head to be adjusted into an infinite variety of positions. It is therefore 100 seldom or never necessary to adjust the plate 55 relatively to the center post 44, but nevertheless this can be done if desirable by merely loosening the set screw just mentioned.

In Figures 7, 8 and 9 I show another form 105 of my device, in which the stereoscope head is made in halves, one of which is adjustable relatively to the other.

A standard is shown at 63 and supports the weight of the stereoscope head. The standard has in this instance the form of a flat bar of the shape indicated in Figure 7, and is provided with a slot 64 by and whereof the standard, and parts carried thereby, may be adjusted vertically.

110 A set screw 65, similar in form to the set screw 46 above described, engages and extends through the upper end of the standard 63, and supports thereon a block 66, constituting practically one half of the 115 stereoscope head. A friction plate 63^a similar in form to the friction plate 42^e above described, is disposed between the upper end of the standard 63 and the adjacent portion of the block 66. This block may by 120 hand be turned or adjusted relatively to the standard 63 in the manner above described for the block 44 in its movement relatively to the standard member 55.

125 A shaft 66^a extends through a hole in the 130

block 66, and through a bearing 67 carried by the block, the shaft being thus journaled relatively to the block, and free to be rocked. The shaft carries a knob 68, to be grasped 5 for this purpose by the operator.

Mounted rigidly upon one end of the shaft 66^a is a crank 69, carrying a pin 70. The crank is located within a slot or countersink 71, and thus housed within the block 66, 10 the pin 70 extending outwardly therefrom, as indicated in Figure 7.

A block 72, of a general form mating that of the block 66, is provided with a slot 73 into which the pin 70 extends, as indicated 15 more particularly in Figure 7. The stereoscopic mirrors are shown at 50^a, 51^a.

The block 66 carries a metallic plate 74, sunken into it and held in position by screws 75, as shown in Figure 7. A bolt 76 extends 20 through a hole in the plate 74, and is provided with a head 77 against which the plate 74 is held tightly.

The block 72 carries a plate 78, sunken into it and having a form similar to that 25 of the block 74, and similarly held in position by screws 79. The block 72 is further provided with a slot 80. Located within this slot, and revolvably mounted upon the bolt 76, is a nut 81, the bolt being threaded 30 for this purpose.

The weight of the block 72 is supported upon the bolt 76, which thus acts after the manner of a trunnion. The operator, by slightly turning the nut 81 at intervals, can 35 adjust the freedom of movement of the block 72 relatively to the block 66.

The blocks 80 and 66 are provided with blinders 82, 83.

The block 66 being stationary, the operator 40 by grasping the knob 68 and rocking the shaft 66 can cause the block 72 to rock or turn slightly upon the bolt 76, which thus acts as a pivot. Thus the block 72 is adjustable angularly in relation to the block 45 66, upon the pivot just mentioned, and the adjustment is very exact and under control of the operator.

The stereoscope head as a whole is adjustable angularly in relation to the standard 50 63, since the block 66 carries the block 72, and may by hand be turned or rocked upon the set screw 65 as a center.

The various parts not shown in Figures 55 7, 8 and 9 have the structure and action above described with reference to the other figures.

The operation of my device is as follows:

A pair of plates being selected and placed 60 against the backings 24, 25, and being either trans-illuminated, illuminated by reflected light, or illuminated in any other suitable manner, the plates are brought as nearly as practicable into proper adjustment by turning the illuminating frames 20, 21, upon 65 their carriages 17, 18, and by moving these

carriages toward or from the stereoscope head, in the manner above described. The operator now places his face adjacent the stereoscope head and views the plate by looking directly into the mirrors 50, 51, in the 70 usual manner. He next makes the adjustments above described in detail, and by so doing brings the two images into exact optical coincidence.

It should be noted in this connection that 75 the stereoscope plates, even when carefully placed in position seldom or never coincide exactly without some change in position or some adjustment being made. This is because great exactness is required and because without perfect coincidence of the images as seen by the operator the stereoscopic effect is greatly impaired. It is found in practice that adjustment is desirable, even when the plates are to all superficial 80 85 appearances, in correct position.

I do not limit myself to the precise mechanism shown, as variations may be made therefrom without departing from the spirit of my invention. Neither do I limit myself to the particular form of stereoscope here shown, nor to any special use for which the stereoscope may be employed, nor in every instance to the use of a stereoscope. The scope of my invention is commensurate 95 with my claims.

I claim:

1. The combination, with a pair of supports for stereoscopic objects to be viewed, of a stereoscopic head divided into separate 100 parts, one for viewing each object, one of said parts being adjustable relatively to the other, in a predetermined plane, said stereoscopic head as a whole being adjustable bodily in a plane crossing the plane first 105 mentioned.

2. A device of the character described, comprising a standard, a stereoscopic head mounted upon said standard, means for supporting stereoscopic plates or the like arranged in pairs and adjustable relatively to each other for enabling the operator to place them in predetermined relative positions so that they may be viewed by aid of said stereoscopic head, and means for tilting said stereoscopic head bodily in relation to said standard and to said stereoscopic plates. 115

3. The combination of a pair of supports for stereoscopic objects to be viewed, a stereoscopic head provided with a pair of 120 mirrors disposed at an angle relatively to each other for the purpose of enabling the operator to view said stereoscopic objects, and means for adjusting said mirrors relatively to each other and to said pair of supports. 125

4. The combination of a pair of supports for holding stereoscopic objects to be viewed, a stereoscopic head provided with a pair of mirrors inclined relatively to each 7

- other and by aid whereof said stereoscopic objects are to be viewed, a mounting for supporting said stereoscopic head, said stereoscopic head being revolubly adjustable relatively to said stereoscopic objects, and means for holding said stereoscopic head in different positions into which it may be turned in order to adjust said mirrors relatively to each other and to said stereoscopic objects.
5. In a stereoscope the combination of a pair of illuminating boxes, a table for supporting the same, a stereoscopic head disposed between said illuminating boxes and carrying a pair of mirrors inclined relatively to each other, means for slidably adjusting said head relatively to said illuminating boxes, mechanism controllable at the will of the operator for turning said stereoscopic head into different angular positions
- of adjustment relatively to said illuminating boxes, and mechanism for supporting said head as thus turned into different angular positions of adjustment.
6. The combination of a pair of illuminating boxes and means for adjusting the same, of a stereoscopic head located intermediate said illuminating boxes, means controllable at the will of the operator for adjusting said stereoscopic head in an infinite number of planes relative to said illuminating boxes, means for supporting said head as thus turned into different planes, and a pair of mirrors carried by said stereoscopic head and associated with said illuminating boxes, said mirrors as a unit being adjustable by the adjustment of said stereoscopic head.

ARTHUR MUTSCHELLER.
